UNITED STATES PATENT OFFICE.

JACOB S. JAMMER, OF CUMBERLAND, MARYLAND, ASSIGNOR TO WESTERN ELECTRIC COMPANY, INCORPORATED, OF NEW YORK, N. Y., A CORPORATION OF NEW YORK.

CARRIER-TRANSMISSION SYSTEM.

Application filed December 19, 1924. Serial No. 756,872.

This invention relates to carrier wave transmission and particularly to carrier dispatch systems.

An object of the invention is to provide 5 a simple and efficient carrier system applicable to dispatch or order circuits, such as are used in train dispatching and the like.

In accordance with one feature of the invention means are provided in a carrier 10 transmission system whereby any one of several way-stations in the system may signal and talk with any other specific way-station in the system without interfering with the telephone or telegraph traffic normally associated with the wires connecting 15 the way-stations.

In the system of the invention a single master oscillator located at one of the stations supplies carrier to the transmitting 20 and receiving circuits of all the way-stations along the line. In speech transmission, the master station uses an unbalanced modulator and transmits the unmodulated carrier and one side band, while at the other way- 25 stations, balanced modulators are used to suppress the carrier and transmit a single side band to communicate between stations.

For calling or signaling purposes, each 30 of the way-stations along the line has assigned to it a different frequency which is not equal to the carrier frequency. All of these signaling frequencies assigned to the various way-stations lie within the range of the band filter used for speech transmission, but are separated enough from each 35 other to prevent false signals. The master station is able to signal any one of the other way-stations by simply changing the frequency of the master oscillator so that it 40 equals the frequency normally associated with the specific way-station signaled. Any one of the other way-stations may signal another way-station or the master station by unbalancing its modulator and causing it 45 to oscillate at a frequency equal to the frequency of the specific station to be called. This signaling frequency is received by all of the way-stations, but, in the case of the particular station assigned this frequency 50 for signaling purposes, it passes from a demodulator through a tuned circuit selective to it and is applied to a modulator. This causes an increase in the space current of the modulator, which by means of re-

lays is made to operate signaling equipment. 55 When the circuits are set up for speech transmission, however, the tuned circuit coupling the demodulator to the modulator is retuned to the carrier frequency.

In accordance with another feature of the 60 invention, means are provided whereby substantially no energy is absorbed from the line by the way stations along the line.

In accordance with another feature, means 65 are provided whereby when the master station is communicating with any one of a certain group of way-stations, carrier current is also furnished to the way-stations of another group so that they may communicate with each other.

Other features and advantages of the invention will be clear from the following detailed description read in connection with the accompanying drawings, in which:

Fig. 1 is a diagrammatic view illustrating 75 in simplified form a carrier dispatch system embodying the invention.

Fig. 2 is a diagrammatic view illustrating 80 in detail one of the way-stations of the carrier dispatch system shown in Fig. 1.

Fig. 3 is a schematic view illustrating a modification of the system of Fig. 1.

Fig. 4 is a diagrammatic view illustrating 85 in detail the master station of the system of Fig. 3.

In the various figures of the drawing similar reference characters represent similar elements.

Referring to Fig. 1 a carrier dispatch system is shown comprising a plurality of 90 way-stations 1, 2, 3 and 4, connected across a transmission line ML. At station 1, hereinafter referred to as the master station, a vacuum tube oscillator O is shown, this oscillator providing carrier for all the way- 95 stations along the line. The oscillator O is connected to the input circuit of a modulator M₁. A transmitter circuit T₁ is also connected to the input circuit of the modulator M₁. The output circuit of modulator 100 M₁ is connected through the hybrid coil H₁, band filter BF₁, hybrid coil H₂, and band filter BF₂ to the transmission line ML. A receiving circuit, comprising a demodulator D₁ and the receiver R, is also associated with 105 the line ML through the hybrid coil H₁. An artificial network N₁ is provided for the purpose of balancing the line. A repeater

circuit R_1 is inserted in the line between the band filters BF_1 and BF_2 through the hybrid coil H_2 .

As the apparatus and circuits of way-stations 2, 3 and 4, hereinafter referred to as substations, are practically identical, it will only be necessary to describe station 2. No oscillator is provided at this station, the transmitting and receiving circuits of each of the substations receiving carrier current from the line ML provided by the oscillator O at the master station. At station 2, a transmitter circuit T_2 is connected to the input circuit of the modulator M_2 . The output circuit of the modulator M_2 is associated through the hybrid coil H'_1 , band filter BF'_1 , hybrid coil H'_2 and band filter BF'_2 with the line ML . The receiving circuit comprising the demodulator D_2 and the receiver R' is also associated with the line ML through the hybrid coil H'_1 . A selective network TC couples the output circuit of the demodulator D_2 with the input circuit of the modulator M_2 . As at station 1, a repeater circuit R_2 is inserted in the line between the band filters BF'_1 and BF'_2 through hybrid coil H'_2 , and an artificial network N_2 is provided for balancing the line.

For the oscillator O at station 1, any known type of generator such as a vacuum tube oscillator in which a tuned circuit is provided for determining the frequency of its oscillations may be used. The modulator M_1 may be of the type illustrated and described in the United States patent to Van der Bijl No. 1,350,752, issued August 24, 1920. The modulator M_2 may be of the balanced vacuum tube type designed to suppress the unmodulated carrier such as is illustrated and described in the United States patent to Carson No. 1,343,306, issued June 15, 1920. The demodulators D_1 , D_2 may be of the balanced vacuum tube type such as is illustrated in Fig. 49 of an article entitled "Carrier current telephony and telegraphy" by Messrs. Colpitts and Blackwell, published in the transactions of the American Institute of Electrical Engineers, vol. 40, 1921. The repeater circuits R_1 and R_2 are of the well known two-way, one-element type, and are inserted in the line at each station for the purpose of increasing the transmitting and receiving gains. A repeater gain of three miles is used so that the same amount of energy is returned to the line as is passed into the way-station circuit and therefore substantially no energy is absorbed from the line by the way-stations. The band filters BF_1 and BF_2 at station 1, BF'_1 and BF'_2 at station 2, and the band filters at the other substations are identical, and are designed to suppress all of the components of modulation except one side band, either the upper or lower as desired, and the

unmodulated carrier. These filters and each of the other filters shown throughout the system may be designed in accordance with the principles set forth in the United States patent to Campbell No. 1,227,113, issued May 22, 1917. Two of these band filters are preferably used at each station in order to secure the required balance of the two hybrid coils at each station.

The selective network TC coupling the transmitting and receiving units of station 2 is tuned to some frequency within the side band passed by the band filters at that station, which frequency is not equal to the carrier frequency. This is the frequency normally assigned to the particular way-station and is used for signaling purposes. A different frequency is assigned to each way-station along the line, all of these frequencies being within the transmitted side band.

The details of the carrier dispatch system shown in simplified form in Fig. 1 and modifications thereof are illustrated in Figs. 2, 3 and 4. The operation of the system will be described in connection with these figures.

In Fig. 2, the apparatus and circuits of one of the substations of the system of Fig. 1, such as station 2, are shown in detail. As stated in connection with the description of Fig. 1, the main elements included at this station comprise a transmitter circuit T_2 adapted to be connected to the input circuit of a modulator M_2 , a demodulator D_2 , a selective network TC coupling the modulator M_2 and the demodulator D_2 , receiver R' associated with the output of the demodulator D_2 , band filters BF'_1 and BF'_2 for suppressing one of the side bands received from the modulator M_2 , and the repeater circuit R_2 inserted in the line between the band filters BF'_1 and BF'_2 .

In addition to these elements, signaling apparatus of any suitable kind, such as the bell 11 and the lamp 12 operated by the relays 9 and 10, is associated with the output circuit of the modulator M_2 , and a resonant circuit, comprising an inductance coil 15, feed-back resistance 16 and condenser 17, is adapted to be connected to the modulator M_2 to make it function as an oscillator for signaling purposes.

The operation of the system illustrated in Figs. 1 and 2 will now be described. Suppose the operator at station 2 wishes to communicate with one of the other substations along the line. As shown in Fig. 2, by inserting plug 1 in jack 2, the transmitter circuit T_2 may be connected to the input circuit of the modulator M_2 through transformer 3. This operation will also establish an operating circuit for relay 4. The operation of relay 4 accomplishes two results; first, it connects condenser 5' in parallel with condenser 5 across the output circuit of selective network TC and condenser 6 in parallel with

condenser 7 in the input circuit of network TC, changing the natural frequency of network TC to the carrier frequency instead of the signaling frequency normally assigned to this particular substation; second, it opens the battery lead 8, making it impossible for the signaling relay 9 in the plate circuit of modulator M_2 to operate the signaling equipment comprising the bell 11 and the lamp 12 at this station.

To signal the distant way-station, the variable condenser 17 in shunt to the coil 15 is adjusted until the frequency at which one side of the modulator M_2 oscillates equals the frequency assigned to the particular substation it is desired to signal. Then, key 13 is operated. The operation of key 13 accomplishes three results; first, it establishes an operating circuit for relay 14 and thus short-circuits the demodulator D_2 ; second, it removes the short-circuit from the coil 15; and, third, it connects the feed-back resistance 16 to the coil 15 and condenser 17. As the modulator M_2 is unbalanced and the adjustment of the variable condenser 17 has been made, the signaling frequency is transmitted from the output circuit of modulator M_2 through the transformer 18, hybrid coil H'_1 , band filter BF'_1 , hybrid coil H'_2 , band filter BF'_2 to the main line ML , and is received by all of the several way-stations including the station signaled.

As the apparatus and circuits at all of the way-stations except the master station are similar, the operation at the station signaled will be described also by referring to the circuit shown in Fig. 2. The current of the signaling frequency received from the line ML passes through band filter BF'_2 , hybrid coil H'_2 , band filter BF'_1 , hybrid coil H'_1 and the transformer 19 to the input circuit of the demodulator D_2 . This signaling frequency is amplified by demodulator D_2 and by means of output transformer 20, selective network TC, which in the case of the particular station signaled is tuned to the signaling frequency, and transformer 21, is supplied to the input circuit of the balanced modulator M_2 . The application of the signaling voltage to the modulator M_2 causes its space current to be increased sufficiently to cause the operation of the relay 9 in its plate circuit, which as relay 4 is not operated, establishes an operating circuit for relay 10. The operation of relay 10 rings the bell 11 and lights the lamp 12.

When the station attendant, observing the signal, connects his transmitting circuit T_2 to the modulator M_2 by inserting plug 1 into jack 2, relay 4 is operated which breaks the battery connection 8 to relay 10, extinguishing the lamp 12 and stopping the bell 11 from ringing. The operation of relay 4, in the manner previously described, also tunes

the selective network TC to the carrier frequency.

When the station attendant originating the call releases the signaling key 13, the relay 14 releases also, removing the short-circuit across his receiving unit. Also, the release of key 13 short-circuits the coil 15 and disconnects the feed-back resistance 16 from the coil 15. The carrier circuits are then set up so that the attendants at the two stations may talk to each other.

In speech transmission, voice frequency potentials from the transmitter circuit T_2 by means of the transformer 3 are applied differentially to the grid circuits of the tubes 22 and 23 of the modulator circuit M_2 . Carrier potential from the network TC is applied through the transformer 21 to the common portion of the input circuit of the modulator M_2 . In accordance with the well known action of the balanced modulator, the unmodulated carrier is suppressed in the output circuit of modulator M_2 , but the side band currents, resulting from the interaction of the carrier and speech frequency currents, are reproduced in the output circuit. By means of the transformer 18 and hybrid coil H'_1 , the side band currents are passed to the band filter BF'_1 , which suppresses one of the side bands. One side band, therefore, is transmitted by BF'_1 through hybrid coil H'_2 and a similar band filter BF'_2 to the line ML .

As explained in connection with Fig. 1, a part of the line energy is picked off by means of the hybrid coil H'_2 and amplified in the repeater circuit R_2 and returned to the line. As each station is connected across the main line ML , the gain can be so adjusted that very little energy is absorbed by the way-station.

At the receiving station, the side band current is received from the line ML and passes through band filter BF'_2 , hybrid coil H'_2 , band filter BF'_1 , hybrid coil H'_1 , and transformer 19 to the demodulator D_2 . The demodulated speech currents in the output of the demodulator D_2 are transmitted through the transformer 20 and the low pass filter 25 to the receiver R' .

The low pass filter 25 is inserted in the receiving circuit in order to eliminate the carrier whistle and other objectionable high frequencies. A network 24 is inserted in the transmitter circuit T_2 for the purpose of improving the quality and reducing the load on the modulator M_2 .

The method of signaling between the various substations along the line described above is not applicable to signals sent out by the master station. The method of signaling used by the master station will now be described. As shown in Fig. 1, when the operator at the master station, station

- 1, wishes to signal one of the substations, he may change the frequency of the oscillator O_1 until it equals the frequency normally assigned to the particular substation 5 with which he desires to communicate. This frequency will be passed by the demodulator and the selective network TC of the substation signaled and will operate signaling apparatus at that station in the manner described above in connection with Fig. 2. In 10 the case of signals received by the master station, the gain of the demodulator D_1 may be increased by an additional stage of amplification coupled to the demodulator by a 15 tuned circuit, and signaling apparatus may be operated by a relay in the second stage of the receiving unit. This additional apparatus, not shown in Fig. 1, is illustrated and described in detail in connection with the 20 modified circuit of Fig. 4. The circuit of the master station of Fig. 1 modified in a manner which will be explained later, is shown in detail in Fig. 4, and its operation in speech transmission and signaling will 25 be clear from the description in connection with that figure.

In Fig. 3 is shown schematically a modification of the carrier dispatch system of Fig. 1. At station 1, the master station, 30 two oscillators, O_1 and O_2 , each producing a different frequency or a different range of frequencies, and two corresponding band filters BF_3 and BF_4 , each adapted to pass a different frequency band, are used instead 35 of the single master oscillator O_1 and the single band filter BF_1 at the master station as in Fig. 1. A certain group of substations connected across the transmission line ML, for example, stations 2, 4 and 6 may 40 be allocated frequencies within the range passed by band filter BF_3 , while another group of stations, for example, stations 3, 5 and 7, may be allocated frequencies within the range passed by band filter BF_4 . A 45 suitable switching arrangement is provided whereby when oscillator O_1 is connected to the line ML through modulator-demodulator circuit MD and the band filter BF_3 , then oscillator O_2 will be connected to the line 50 ML directly through its band filter BF_4 . Likewise, the switching arrangement is adapted to connect the oscillator O_1 directly to the line ML through its band filter BF_3 , when oscillator O_2 is connected to the line 55 ML through the modulator-demodulator circuit MD and the band filter BF_4 .

Now, if the master station is signaling or talking with any one of the substations 2, 4 and 6, selective to frequencies within the 60 range passed by band filter BF_3 , oscillator O_1 will be connected to line ML through the modulator-demodulator MD and the band filter BF_3 . At the same time oscillator O_2 will be connected directly to the line ML 65 through its band filter BF_4 , and stations 3, 5 and 7 selective to frequencies within the range passed by band filter BF_4 , will still be supplied with carrier from the oscillator O_2 so that they may signal to and talk with each other. Likewise, when the master station, using carrier from oscillator O_2 , is 70 connected to the line so as to signal or talk with stations 3, 5 and 7, then stations 2, 4 and 6 will be supplied with carrier from oscillator O_1 . 75

The circuits and switching arrangements of the master station shown in Fig. 3 are shown in detail in Fig. 4.

The circuit shown in Fig. 4 differs from that shown at station 1 of Fig. 1 in that a second oscillator O_2 , a second band filter BF_4 , and keys S_1 , S_2 and S_3 have been added. Also, an additional stage of amplification A_1 and suitable signaling apparatus such as lamp 36 and bell 38 operated by relays 35 and 37, associated with the output of the demodulator D_1 , not shown in Fig. 1 but referred to in the description of that figure, are shown in detail in Fig. 4.

The operation of the modified system will 90 now be described referring to Fig. 4. With the keys S_1 , S_2 and S_3 in the normally unoperated positions shown, oscillator O_1 is connected through transformers 28 and 29 to the input circuit of modulator M_1 and through transformers 28 and 30 to the input circuit of demodulator D_1 . The output circuit of modulator M_1 by means of transformer 31, and the input circuit of demodulator D_1 by means of transformer 32 are 95 connected through the hybrid coil H_1 and the band filter BF_3 to the line ML. With the keys as shown, the oscillator O_2 is connected to the line ML through its band filter 100 BF_4 . Therefore, the carrier frequencies produced by the oscillators O_1 and O_2 will both be present on the line ML. Now, if the operator at the master station wishes to talk with any of the substations selective to a 105 frequency within the band passed by band filter BF_3 , to signal that station the variable condenser 27 in the tuned circuit of oscillator O_1 is adjusted so that the particular signaling frequency is produced by the oscillator O_1 and transmitted to the line ML 110 through the band filter BF_3 . The signaling frequency will be received by all of the substations along the line, and, in the case of the particular station assigned that frequency, will operate its signaling apparatus, 115 as described in connection with Fig. 2. The carrier circuits between the substation and the master station may then be set up in the manner described previously in connection with Fig. 2.

With the carrier circuits set up, the carrier wave from oscillator O_1 is supplied to the modulator M_1 and is modulated with voice frequency currents from the transmitter circuit T , supplied to the modulator M_1 through 120

transformer 33. The components of modulation in the output circuit of modulator M_1 , comprising both side bands, and the unmodulated carrier will be passed by transformer 31 and hybrid coil H_1 to band filter BF_3 . Band filter BF_3 will suppress one of the side bands and transmit the other side band and the unmodulated carrier to the demodulating apparatus of the distant substation and 10 thence to its receiver. Meanwhile, the frequency produced by oscillator O_2 , which is connected to the line ML through its band filter BF_4 , will also be received by all of the substations along the line, and in the case 15 of the particular group of stations, 3, 5 and 7, selective to frequencies within the band passed by band filter BF_4 , may be used for signaling and communicating between stations, in the manner described in connection 20 with Fig. 2.

In like manner, the operation of the keys S_1 , S_2 and S_3 will connect oscillator O_2 through modulator M_1 and demodulator D_1 , hybrid coil H_1 and band filter BF_4 to the line 25 ML , and oscillator O_1 directly to the line ML through its band filter BF_3 , thereby making it possible for the master station to signal and talk with any of the substations, 30 3, 5 and 7 in the group selective to frequencies within the band passed by the band filter BF_4 , and also to provide carrier current to the other group of stations, 2, 4 and 6 selective to frequencies within the band 35 passed by band filter BF_3 , so that they may signal and talk with each other.

Any of the substations along the line may signal the master station by simply unbalancing its modulator and transmitting the 40 particular signaling frequency assigned to the master station, in the manner described in connection with Fig. 2, which frequency will pass through either band filter, BF_3 or BF_4 , depending upon its value, through the hybrid coil H_1 and transformer 32 to the 45 input circuit of the demodulator D_1 . This frequency will be passed by the demodulator D_1 through transformer 34 and the network TC_2 , which is selective to it, and will be amplified by the amplifier A_1 . The consequent increase in space current of amplifier 50 A_1 will operate relay 35 in its plate circuit. The operation of relay 35 will close an operating circuit to light lamp 36 and operate relay 37 to ring bell 38.

55 Although, in connection with the description of the various modifications of the system embodying the invention, it was stated that the signaling frequencies associated with the various way-stations of the system 60 were to lie within the range of the band filter used for speech transmission separated enough from each other to prevent false signals, it is to be understood, however, that signaling frequencies outside this range may

be used, and the signaling current passed 65 around the band filter through suitable tuned circuits.

The invention set forth herein is, of course, susceptible of various modifications and adaptations other than those shown, 70 and the figures and description given herein are to be taken merely as illustrative of the invention and are not to be considered as limiting its scope except as defined in the 75 appended claims.

What is claimed is:

1. In a carrier wave system, a master station and a plurality of way stations, means only at the master station to generate carrier waves and transmit them to said way 80 stations, means at each way station to modulate carrier waves from the master station in accordance with signals and to transmit to another way station modulation components only while suppressing transmission 85 of the unmodulated carrier component, and means at each way station for combining waves of the carrier frequency received from the master station with the modulation components received from another way 90 station to receive said signals.

2. In a carrier wave system, a line, a master station and a plurality of way stations connected to said line, means only at the master station to generate carrier waves and transmit them to said line, modulating and demodulating means at each way station to receive carrier and sideband components from said line but to transmit only sideband 100 components to said line, and an amplifier connected between the said means at each way station and said line, each amplifier comprising means to return to the line carrier waves equivalent in amount to the carrier waves absorbed by said way station. 105

3. In a carrier transmission system, a transmission line, a plurality of stations connected to said line, a high frequency source at one of said stations for supplying a carrier wave to said line, means at a second of said stations for receiving said carrier wave from said line, means at said second station for modulating said carrier wave in accordance with speech signals, means at 110 said second station for suppressing the unmodulated carrier component and one side band component of said signal-modulated wave, and for transmitting the other side band component of said signal-modulated wave to a third one of said stations, means at said third station for demodulating the transmitted side band component, means at 115 said third station for selectively receiving the speech signals from the demodulated waves, means at said third station for selecting the unmodulated carrier component from said demodulated waves, means at said third station for modulating the selected

120

125

carrier component with other speech signals, means for suppressing the unmodulated component and one side band component from said signal-modulated wave produced at said third station, and for transmitting the other side band component of said signal-modulated wave produced at said third station to said second station.

4. In a signaling system, a transmission line, a plurality of stations connected to said line, means for supplying said transmission line with a wave of carrier frequency, means at one of said stations for receiving said carrier wave, a circuit associated with said receiving means normally selective to a frequency not equal to said carrier frequency, means for tuning said circuit to said carrier frequency, a balanced-modulator circuit supplied with carrier from said selective circuit when tuned to carrier frequency, means for unbalancing said balanced modulator circuit to make it function as an oscillator to transmit a signal over said transmission line to a second one of said stations, means at said first-mentioned station to change the frequency of the transmitted signal to a signaling frequency normally assigned to said second station, a signaling device at said second station, and means at said second station responsive to the wave of changed frequency received from said first mentioned station to operate said signaling device.

5. A carrier transmission system comprising a transmission line, a high frequency source for supplying carrier to said line, a plurality of way-stations connected across said line receiving carrier from said line, and means including a repeater circuit at one of said way-stations arranged to return to said line substantially the same amount of energy as is absorbed from said line by said way-station.

6. In a carrier transmission system, a transmission line, a plurality of way-stations comprising a master station and a plurality of substations, a source of carrier waves at said master station, a second source of carrier waves at said master station, said second source producing waves of a different range of frequencies than the first mentioned source, means at said master station to modulate the carrier waves from either source in accordance with speech signals, a band filter at said master station, said band filter being adapted to pass the unmodulated carrier from said first mentioned source and frequencies within the range of the side band produced by modulation of the carrier wave from said first mentioned source with speech signals, and to suppress all other frequencies, a second band filter at said master station, said second band filter being adapted to pass the unmodulated carrier wave from said second source and frequencies within the range produced by the modulation of the

carrier from said second source with speech signals, and to suppress all other frequencies, one group of said substations being selective to frequencies passed by said first mentioned band filter, a second group of said substations being selective to frequencies passed by said second band filter, and switching means adapted for associating either of said sources with said line through the modulating means and the band filter passing the frequency generated by the associated source, while associating the other source with said line directly through the other band filter.

7. In a transmission system, a transmission path over which carrier frequencies may be transmitted, a plurality of signaling stations associated therewith, a high frequency source at one of said stations supplying carrier current to said line, means at a second of said stations for receiving said current from said line, means at said second station to modulate said carrier current with speech signals, and to suppress the unmodulated carrier component, a band filter at said second station adapted to pass over said line to a third one of said stations a definite band of frequencies of the modulated wave, and to suppress all other frequencies, another band filter at said third station adapted to pass frequencies within the range of the transmitted band, and to suppress frequencies outside said range, means associated with said other band filter to demodulate said transmitted band, means associated with the output of the demodulating means to selectively receive the speech signals from the demodulated waves, a tuned circuit associated with the output of said demodulating means to select the carrier wave from said demodulated waves, means at said third station to modulate the selected carrier wave with other speech signals, and to suppress the unmodulated carrier, and means comprising said other band filter to transmit one side band of the components of modulation to said second station.

8. The combination in a high frequency signaling system of a transmitting line, two sources of high frequency current of different frequencies, means for modulating the high frequency current from either of said sources in accordance with speech, a band filter inserted in said line, adapted to pass frequencies within the range of one side band component formed by the modulation of the current from one of said sources with speech, and to suppress all other frequencies, a second band filter inserted in said line adapted to pass frequencies within the range of one side band component formed by the modulation of the current from the other of said sources with speech, and to suppress all other frequencies, means for demodulating speech-modulated waves received over said line through either of the

band filters, means associated with the output of the demodulating means to selectively receive the speech signals from the demodulated waves, and switching means adapted 5 to associate one of said sources with said line through the band filter adapted to pass its frequency when the other of said sources is associated with the line through said modulating means, said demodulating means 10 and the other of said band filters.

9. In a signaling system, a transmission line, a station associated with said line, a source of carrier waves at said station, means for changing the frequency of said waves 15 from said source for signaling purposes, means for supplying said carrier waves to said line comprising a band filter adapted to pass a definite band of frequencies including said changed carrier frequency, a 20 second station associated with said line, a second band filter at said second station adapted to pass the same band of frequencies including the carrier wave of changed frequency as the band filter at the first mentioned station, a signaling device at said second station, a network associated with said second band filter normally selective to the changed carrier frequency, a vacuum 25 tube modulator at said second station associated with said network for amplifying said wave of changed carrier frequency, means in the output of said modulator responsive to the amplified wave of changed carrier frequency to operate said signaling 30 device.

10. In a signaling system a transmission line over which carrier current is supplied to a plurality of stations, a station associated with said line, a vacuum tube de- 40 modulator at said station, a band filter adapted to pass a definite band of frequencies, including the frequency of said carrier wave, supplying carrier current to said de-modulator from said line, a vacuum tube 45 modulator, a network, normally selective to a frequency within the range of the band passed by said band filter other than the carrier frequency, coupling the output of said demodulator with the input of said 50 modulator, means to retune said network to the carrier frequency to supply carrier current to said modulator, means comprising an oscillating circuit to adapt said modulator to function as an oscillator for signaling 55 purposes, means to tune said oscillation circuit to control the frequency of the oscillation transmitted by said modulator through said band filter over said line to a second of said stations, the transmitted 60 frequency being a signaling frequency within the range of said band filter, a second band filter at said second station adapted to pass said signaling frequency, a signaling device at said second station, a network as- 65 sociated with said second band filter nor-

mally selective to said signaling frequency, a vacuum tube modulator at said second station associated with said network for amplifying said wave of signaling frequency, means in the output of said modulator re- 70 sponsive to the amplified wave of signaling frequency to operate said signaling device.

11. In a wave transmission system, a line, a station connected across said line, a source of carrier oscillations at said station, 75 means at said station to modulate said carrier oscillations with speech variations, a band filter at said station to suppress one side band component, and to transmit the other side band component, and the unmodu- 80 lated component of the speech-modulated wave over said line, a second station connected across said line, a band filter at said second station to pass said side band component and said unmodulated component of 85 the transmitted wave, and to suppress all other frequencies, means at said second station to demodulate the carrier oscillations and the speech variations of said side band component passed by said band filter at 90 said second station, means associated with the output of the demodulating means to selectively receive said speech variations, a tuned circuit associated with the output of 95 said demodulating means to select said carrier oscillations, means at said second station to modulate the selected wave with other speech variations, and to suppress the unmodulated component of the modulated wave, and means to suppress one side band 100 component and to transmit the other side band component of said signal modulated wave generated at said second station to said first mentioned station.

12. In a wave transmission system, a 105 transmission line, a high frequency source to supply a carrier wave to said line, a plurality of stations receiving said carrier wave from said line, means at one of said stations to modulate said carrier wave in accordance 110 with speech signals, and to suppress the unmodulated component of the speech modulated wave, a band filter at said station to suppress one of the side band components 115 of said speech modulated wave, and to transmit the other side band component of said speech modulated wave over said line to another of said stations, a band filter at said other station to pass said transmitted side band component, means at said other 120 station to demodulate said speech signals and said carrier wave, means associated with the output of said demodulating means to selectively receive said speech signals, means 125 associated with the output of said demodulating means to select said carrier wave, means at said other station to modulate the selected carrier wave with other speech signals, and to suppress the unmodulated component of said speech modulated wave gen- 130

erated at said other station, and a second band filter at said other station to suppress one side band component of the generated wave, and to transmit the other side band component of said generated wave over said line to the first mentioned station.

13. In a carrier transmission system, a transmission line, a plurality of stations connected to said line, a high frequency source at one of said stations to supply a carrier wave to said line, said carrier waves being supplied to all of said stations from said line, means at another of said stations

to modulate said carrier wave in accordance with speech signals, and to suppress the unmodulated carrier, means at said other station to suppress one side band component, and to transmit the other side band component of the signal-modulated wave over said line to a third station, and means at 20 said third station to demodulate said carrier wave to reproduce said speech signals.

In witness whereof, I hereunto subscribe my name this 17th day of December A. D., 1924.

JACOB S. JAMMER.
